UNITED STATES PATENT OFFICE.

ROBERT W. NICHOLLS, OF PALISADES PARK, NEW JERSEY, ASSIGNOR TO GOLD SEAL CO., OF PALISADES PARK, NEW JERSEY, A CORPORATION OF NEW JERSEY.

REPEATING DEVICE FOR PHONOGRAHS.

Application filed February 13, 1922. Serial No. 536,014.

To all whom it may concern:

Be it known that I, ROBERT W. NICHOLLS, a citizen of the United States, and a resident of Palisades Park, county of Bergen, and

5 State of New Jersey, have invented a new and useful Improvement in Repeating Devices for Phonographs, of which the following is a specification.

The object of my invention is to provide 10 a self-contained device of this class which can be used on a phonograph with certainty and convenience and without any change or modification in the phonograph of any kind whatsoever. This object is accomplished by 15 my invention, one embodiment of which is hereinafter more particularly set forth.

For a more detailed description of my invention, reference is to be had to the accompanying drawings, forming a part hereof, 20 in which—

Figure 1 is a perspective view of one embodiment of my invention, a portion of a phonograph of the disc type, being shown in dotted lines.

25 Figure 2 is an enlarged detailed view of a portion of the apparatus.

Figure 3 is a sectional view, taken on the line 3—3 of Figure 2, looking in the direction of the arrows.

30 Throughout the various views of the drawings, similar reference characters designate similar parts.

My improved repeating device 1 is mounted on a record 2 of a phonograph table 3 35 which has the usual center pin 4 and which is driven in the conventional manner, as by a motor which is not shown. Sound is produced in the usual way by means of a needle 5 connected to a sound box 6 which is carried by the tone arm 7 which is pivotally mounted in the usual way. As the phonograph employed is the conventional instrument, further description is unnecessary.

The repeating device 1 is preferably 45 pressed out of celluloid so as to form a cam disc 8 with a cam groove 9 which runs from approximately the inner part of a record to the outer part and the ends of this groove are connected by an opening 10 with two laterally extending ends, one 11 running to the inner end of the groove 9 and one 12 connecting with its outer end.

50 The center of the disc 8 carries a triangular opening 13 which has rounded corners and a depressed edge as indicated by the

drawing. This triangular opening has two short and one long side, the latter marked 14 and which is the side remote from the opening 10.

At the extreme outer edge of the disc 8 60 and near the opening 10 is fixed a post 15 which preferably has an inclined flange 16 which is adapted to pass under a record 2 or the turn table 3, and this post is preferably surrounded by a cushion of rubber 17 or 65 other similar material.

To improve the appearance of the disc 8 the post 15 is preferably covered by a cover plate 18 and is provided with a number of ribs 19 and other ornamental devices are 70 added where desired. In the preferred embodiment of my invention there are a number of openings 20 which make the disc 18 lighter and better looking than it would be 75 if solid.

In the preferred embodiment of my invention, there is a peculiar relation between the edge 14 and the pin 15 which will now be described. It will be noted that this edge is not equidistant from the pin 15, but is 80 sloped so that the end nearest the opening 11 is also nearer the pin 15 than the other end. The purpose of this will appear below.

The operation of this repeater is as follows, assuming the parts to be as indicated 85 in Figure 1.

Assuming that the record 2 is turning as indicated by the arrows, the cam disc 8 turns with the same until an edge of the opening 10 engages the needle 5 and then the record 90 is played without interference until the needle 5 reaches the inner end of the opening 10 and passes to the opening 11. As soon as the needle runs by the edge of the opening 10, with which it has been in engagement, 95 and passes into the opening 11, the cam disc 8 will turn with the record 2 and then the needle will rise into the cam groove 9. As soon as it does this it begins to drag in this 100 groove and thereby retard the movement of the disc on the record. This retarding causes the center pin 4 of the turn table 3 to engage the edge 14 with increasing tension whereby the pin 15 is locked against the record or turntable, preferably the record 105 and remains so locked until the needle 5 is at the outer end of the groove 9. When near this outer end the cam plate 8 begins to shift outwardly and the lock is released and as 110 soon as the needle is out of the groove and

enters the opening 12, the drag ceases, the cam plate 8 is entirely released and is placed against the needle at the outer end of the edge 10 and then the device continues to operate the same as before and the needle shifts to the inner end of the opening 10, as above described. This cycle of operations is repeated indefinitely with a positive locking of the disc 8 to the record or turn table when the needle 5 enters the groove 9 and a positive release when the needle leaves this groove.

If the pin 15 is intended to engage the turn table, it may be necessary to extend it and to place it at a point which is more remote from the pin 4 at the center of the turntable. In the preferred embodiment of my invention this pin 15 engages the record on which rests the cam disc 8.

20 While I have shown and described one embodiment of my invention, it is obvious that it is not restricted thereto, but that it is broad enough to cover all structures that come within the scope of the annexed claims.

25 Having thus described my invention, what I claim is:

1. A repeating attachment for sound reproducing machines having the usual turntable with a center pin, a playing stylus and sound record; a disk having therein a triangular opening that is adapted to lie on the record with said opening over the center pin, and an opening, the edge of which engages the stylus to hold the disk stationary during the reproducing operation, a groove in the disk to guide the needle to starting position after said record has been played, a clutch pin extending below the disk and over the edge of the record, which is adapted to be brought into engagement with said edge when the disk is allowed to start in rotation and to be released therefrom when the disk is again arrested by engagement with the stylus.

40 2. A phonograph repeater made of a suitable material and adapted to rest lightly upon the record, said repeater having a slot opening therein one edge of which engages

the stylus while reproducing and arrests its rotation, a triangular opening that goes over the center pin of the turn-table, a groove that extends from one end of the said slot opening to the other by which the stylus is carried back to the starting point after a record has been played, and a pin which is brought into gripping contact with the edge of the disk by the shifting of the repeater due to the engagement with the center pin of an inclined side of the triangular opening when the repeater is released to rotate and freed from such engagement when the repeater is again arrested by engagement of the stylus with the edge of the said slot opening.

3. A phonograph repeater consisting of a sheet of celluloid adapted to rest lightly upon a sound record having a substantially radial slot therein for engaging the stylus and arresting its movement of rotation during the playing of the record, a triangular opening that goes over the pin of the turn-table, a clutch to engage with the record disk and check its rotation operated by the movement of the repeater when released and permitted to start in rotation by disengagement with the stylus, and a spiral groove connecting the two ends of the radial slot.

4. In an automatic repeating attachment for sound reproducing machines having the usual turn table spindle, playing stylus, and sound record; a member having an elongated hole going over the spindle and arranged on the record, means on said member to engage the stylus to hold the member stationary during the reproducing operation, a groove in said member for guiding the needle to starting position after said record has been played, clutch means on said member formed to engage the edge of the record, when the stylus enters said groove, and clutch the member to the record to rotate therewith, and releasable therefrom when the stylus re-engages the first named means.

In testimony whereof, I have hereunto set my hand this 10th day of February, 1922.

ROBERT W. NICHOLLS.
